James Horton

Assignor to D. Stuart and R. Peterson.

FIG. 1.

Patented June 29. 1858.

— FIG. 2 —

Dec. 1016

J. Horton, of Philadelphia, Pa.
assignor to
David Stuart S.R. Peterson, of same place.
Letters Patent, No. 1016 - dated June 29th 1858.

The schedule referred to in these Letters Patent and making part of the same.
To all whom it may concern:

Be it known, that J. James Horton, of the City of Philadelphia and State of Pennsylvania, have invented or produced a new and original design for plates forming part of a Cooking Stove termed the "Iron Witch", and I do hereby declare the following to be a full and exact description of the same reference being had to the accompanying drawing which form a part of this specification and in which,

Fig. 1. represents the side plate of the "Iron witch" cooking stove;
Fig. 2. the front plate of the same.

The side plate A is edged with a moulding a of plain beads and has a trellised panel b at the bottom, and near the front end a panel B with a foliated ornament in alto-relievo surrounded by a plain beaded moulding c and a denticulated moulding d. An oven door D is hinged to the side plate, and this door has a foliated ornament and is edged with both a plain beaded and a denticulated moulding corresponding to those of the panel B.

The front plate, Fig. 2, has mouldings f corresponding to the mouldings a of the side plate, and has two doors E edged with denticulated mouldings h, each door having a panel i edged with plain mouldings j and a sliding damper I consisting of two plates k, k, trellised bars.

Des. 1016

I claim the combination and arrangement of ornamental figures and forms represented in and by the accompanying drawing, forming together an ornamental design for the front and side plates of a cooking stove.

In testimony whereof, I have signed my name to this specification before two subscribing witnesses.

Witnesses.
